UNITED STATES PATENT OFFICE

143,923

DESIGN FOR A RING

Irving Lieber, New York, N. Y.

Application September 27, 1945, Serial No. 122,360

Term of patent 14 years

(Cl. D45—10)

To all whom it may concern:

Be it known that I, Irving Lieber, a citizen of the United States, residing in New York, in the county of Bronx and State of New York, have invented a new, original, and ornamental Design for a Ring, of which the following is a specification, reference being had to the accompanying drawing, forming a part thereof.

In the drawing, the figure is a perspective view of a ring showing my new design.

The design is continuous around the ring circumference.

I claim:

The ornamental design for a ring, as shown and described.

IRVING LIEBER.
